UNITED STATES PATENT OFFICE.

MYER COHEN, OF REVERE, MASSACHUSETTS.

COIN-CONTROLLED LOCK.

Application filed June 1, 1920. Serial No. 385,418.

To all whom it may concern:

Be it known that I, MYER COHEN, a citizen of the United States, residing at Revere, county of Suffolk, State of Massachusetts, 5 have invented an Improvement in Coin-Controlled Locks, of which the following description, in connection with the accompanying drawing, is a specification, like characters on the drawing representing like 10 parts.

This invention relates to a coin-controlled lock for a drawer, container or other receptacle which requires the insertion of one coin to permit the drawer to be locked and the 15 key to be removed and the insertion of another coin to permit the drawer to be unlocked again. The invention is capable of being put to a variety of uses, but I have particularly in mind its use as applied to 20 a cabinet containing a plurality of drawers and which is adapted to act as a depository for articles to be cleaned, such, for instance, as soiled gloves, or other soiled articles, and as a receptacle to receive these articles again 25 after they have been cleansed.

When used in this way I propose to provide a cabinet with a plurality of compartments or drawers, each having its individual key. This cabinet may be placed in some 30 convenient location, and if any individual wishes to have his gloves or any other similar articles cleansed, he will place them in one of the drawers and then insert the proper coin and lock the drawer, taking the 35 key with him. The concern that does the cleansing will by the use of a master key open the drawers at stated intervals, remove the articles and cleanse them and replace them in the drawers again and lock the 40 drawers. After a specified time, the customer or patron will come back to the cabinet and by inserting another coin, he can unlock his particular drawer with the key which he has removed therefrom and thereby 45 gain access to the cleansed articles therein. The sum of the two coins thus inserted to lock the drawer and then to unlock it again will be the amount charged for cleaning the gloves or other articles. If, for 50 instance, the charge is ten cents for cleaning a pair of gloves, then the device may be constructed so that it will require the insertion of a five cent piece to lock the drawer after the soiled gloves are inserted, 55 and then the insertion of another five cent piece to enable the patron to unlock the

drawer again with the key with which the drawer was locked. The above is, however, only one way in which the invention may be used, and I do not wish to be limited to 60 its use in this particular manner.

In order to give an understanding of my invention, I have illustrated in the drawings a selected embodiment thereof which will now be described, after which the novel 65 features will be pointed out in the appended claims.

In the drawings, Fig. 1 is a view of the drawer showing the coin-controlled lock in elevation;

Fig. 2 is a section on substantially the line 2—2, Fig. 1;

Fig. 3 is a section on the line 3—3, Fig. 1;

Fig. 4 is a section on the line 4—4, Fig. 1;

Fig. 5 is a section on the line 5—5, Fig. 1; 75

Fig. 6 is a section on the line 6—6, Fig. 1;

Fig. 7 is a sectional view of the barrel for the key;

Fig. 8 is a front view thereof;

Fig. 9 is a view of the master key; 80

Fig. 10 is a front view of a cabinet embodying my invention;

Fig. 11 is a plan view thereof;

Figs. 12 to 22, inclusive, are diagrammatic views showing the positions of the parts in 85 different stages of the operation of locking the drawer and unlocking it again.

My invention can be applied to containers or receptacles of various different kinds and is herein shown as applied to the individual drawers of a cabinet. I have shown at 1 in Figs. 10 and 11 a polygonal cabinet arranged with drawers on all sides thereof, but the invention, of course, can be embodied in a wall cabinet or in any other kind of cabinet. 95

The different drawers in this cabinet are indicated at 2 and each drawer has its individual key for locking and unlocking the same, and each key is different from any 100 other key.

The lock for each drawer comprises a bolt 3 which operates at the front end 4 of the drawer and is adapted to be projected upwardly beyond the top of the drawer and into a keeper in the rail 5 of the cabinet above the drawer, as usual in the drawers of a desk or similar device. This bolt 3 is connected by an arm 6 with a key-operated barrel 7 which is rotatably mounted. The barrel has an arm 8 extending therefrom to which the lower end 6 of the bolt 3 is piv- 105 110

oted, as shown at 9. This lower end of the bolt is curved slightly, as best seen in Fig. 1. When the barrel is turned with the arm 8 standing upright, as shown in Figs. 1 and 5 3, the bolt 3 will be projected. When the barrel is turned through 180° so as to bring the arm 8 below the barrel, then the bolt will be withdrawn. The curvature in the arm 6 permits this movement of the bolt 10 and barrel. The barrel 7 is provided with a key slot 10 adapted for the reception of a key 11. The bolt and the barrel are situated directly back of the front 4 of the drawer, and the latter is provided with an opening 15 12 through which the key may be inserted into the barrel. The barrel and key are constructed so that the key can only be withdrawn when the bolt is projected, the key being locked in the barrel when the bolt is 20 retracted. This is provided for by making the key 11 with the extension 13 which projects beyond the barrel when the key is inserted, as shown in Fig. 1, and by providing a slot 14 in a fixed guard plate 15, which 25 slot is in line with the extension 13 when the key is in the position shown in Fig. 4 with the bolt projected. When in this position the key can be withdrawn, but when the key is turned 180° thereby to bring the extension 30 13 on the upper side of the barrel, said extension comes behind a solid portion of the plate 15 and thus prevents the key from being withdrawn. The extension 13 of each key will be provided with a specially-formed 35 serrated edge 150 which matches with the serrated edge 16 of a plate 17 that is fixed in the lock. Each key will have a differently-shaped serrated edge 150 and the lock for each key will have a plate 17 with a complementally-shaped edge 16, and, therefore, 40 the only key which can be used in any lock is that which corresponds to the particular plate 17 of the lock.

45 My improved lock is so designed that it cannot be operated to lock the drawer, as shown in Fig. 3, until a coin of the proper value has been dropped into the coin slot, and is so constructed that after the key has been thus removed the bolt cannot be withdrawn thereby to unlock the drawer when the key is again inserted except by the insertion of another coin. I accomplish this 50 herein by providing a coin-actuated member which normally prevents the barrel from being turned, but which is actuated to release the barrel upon the insertion of a coin, which member is also constructed so that it will lock the barrel from turning movement after the key has been inserted into the key slot for the purpose of unlocking the drawer, but which releases the barrel when another coin is inserted.

55 In the embodiment herein shown this coin-actuating member is indicated at 19 and is in the form of a lever pivoted at 20 to the hous-

ing 21 that receives the lock and which is provided with a weighted end 22 that extends over the barrel 7. The opposite end 23 is a coin-receiving end and is situated beneath a coin chute 24 so that when a coin 70 25 is deposited into the chute 24, it will drop onto the end 23 of the member 19. The counter weight 22 is so proportioned that the weight of a coin on the end 23 will overbalance the counterweight and turn the member 75 19 about its pivot.

The slot 10 in the barrel 7 is open on one side of the barrel and at the other side it is formed with the widened portion 26 which extends through the side of the barrel. When the drawer is unlocked, the barrel is turned so that the open side of the slot 10 is at the top of the barrel. The member 19 is formed with a depending projection 28 which is adapted to enter the slot 10 when said member assumes the normal position illustrated in Fig. 12. The key 11 is provided on opposite edges with the notches 27 situated so that when the key is fully inserted into the barrel the notches will come beneath the projection 28. Consequently, when the bolt 3 is withdrawn and the drawer unlocked, as shown in Fig. 12, the projection 28 will occupy the slot 10 in the barrel and also the notch 27 of the key and the barrel is thereby 95 locked from turning movement. This is the position shown in Fig. 12, and, therefore, when the drawer is unlocked with the key in the lock, the barrel is normally locked from turning movement by the member 19. 100 Moreover, when the key is in this position the projection 28 occupies the notch 27 of the key and thus prevents the key from being withdrawn so that the member 19 acts normally both to lock the barrel from being 105 turned when the drawer is unlocked and to lock the key in the barrel.

When a coin is deposited in the coin slot 24 the weight of the coin on the end 23 of the lever will depress the latter thereby 110 removing the projection 28 from the slot in the barrel and from the notch 27 in the key, thus permitting the key to be operated to lock the drawer. When the barrel is turned into the position shown in Figs. 1 and 3, and 115 the member 19 is in its horizontal position shown in Fig. 20, the projection 28 will occupy the portion 26 of the slot and thus prevent the barrel from being turned and will also occupy one of the notches 27 in the key, 120 thus preventing the key from being withdrawn. The insertion of another coin in the coin slot 24 will again depress the member 19 thereby to unlock the barrel and permit the lock to be actuated. 125 The member 19, therefore, operates to lock the barrel from turning movement both when the drawer is unlocked and when the drawer is locked.

130 Situated beneath the end 23 of the member

19 is a magnet 37 which is constructed so that when the member 19 is fully depressed by a coin, the end 23 thereof will be brought against the magnet and the magnetic attraction of the latter will overbalance the counterweight 22 and hold the member 19 in this depressed position until at a certain point in the cycle of operations the member 19 is positively returned to its normal operative position. For thus controlling the position of the member 19 the barrel 7 is provided with a gear 29 which meshes with a rack 30 that is slidably mounted in ways 31 and that carries at its outer end a head 32 which functions both as a stop to limit the coin-actuated movement of the member 19 under certain conditions and also as a cam to raise the coin-actuated member 19 off from the magnet under other conditions. For the latter purpose the head 32 is provided with a cam face 33 and the member 19 is provided with an extension 34 which is engaged by the cam face 33 when the rack moves to the left. The member 19 also has an arm 35 loosely pivoted thereto at 36 which co-operates with the rest 32 to limit the downward movement of said member under certain conditions.

Before describing the operation of the device, I will refer briefly to one way in which I proposed to use the invention, and that is in connection with a cabinet adapted to receive from patrons soiled gloves, handkerchiefs, collars or other similar articles of laundry and to deliver said articles again to the patrons after they have been cleaned. When used in this way, any patron or customer who has a pair of gloves, collars, handkerchiefs or similar articles which are to be cleansed will come to the cabinet, select an unlocked drawer with the key in it, open the drawer and insert the gloves or other articles to be cleansed. The patron will then close the drawer, but before locking it, it will be necessary for him to insert a coin in the coin slot. The value of the coin thus inserted will be one-half of the total amount to be charged for cleansing the article. The insertion of the coin in the slot permits the drawer to be locked and the key to be withdrawn. The patron keeps the key for the purpose of unlocking the drawer and removing the articles after they have been cleansed. The proprietor of the cleansing establishment will, of course, have a master key by which he can secure access to the drawers and remove the articles for the purpose of cleansing them and for the purpose of replacing them in the drawers after they have been cleansed. After a suitable length of time and after the articles have been cleansed and replaced in the drawer, the patron returns to the cabinet with his key, inserts the key in the lock and then is obliged to drop another coin of equal value as the first coin in the coin slot

in order to permit him to unlock the drawer. Having unlocked the drawer he may remove the cleansed article, and the two coins which have been deposited, one when the article is placed in the drawer, and the other when the article is removed, amount to the charge which will be made for cleansing the article.

These cabinets may be placed in the corridors of hotels, in office buildings, or any other location convenient to the patrons.

The manner in which the device herein described functions to perform the locking and unlocking operations above described is illustrated diagrammatically in Figs. 12 to 22 which show various stages in the process. In these figures, I have illustrated simply the essential parts of the lock.

Fig. 12 shows the condition of the parts when the drawer is unlocked ready to receive the article to be cleansed. In this case the barrel 7 is turned so that the arm 8 is depending downwardly, as shown, and the key 11 is in the lock, and the projection 28 will be occupying one of the notches 27 of the key and will also occupy the slot 10 in the barrel 7. The rack 30 is at its extreme position to the left and the head 32 is situated beneath the extension 34. Since the drawer is unlocked the patron may open the drawer and deposit the article in it. When the drawer is closed again, the patron will deposit a coin 25 in the slot 24 and the weight of the coin will overbalance the weighted end 22 of the lever 19, thereby depressing the lever into the position shown in Fig. 13. This brings the extension 34 onto the head 32, the latter operating to stop the downward movement of the lever 19 before it has moved into a position to permit the coin 25 to drop out of the slot 24. The coin will thus be held on the end 23 of the member 19 and between the latter and the corner 38 of the coin slot. The turning of the member 19 into the position shown in Fig. 13 will withdraw the projection 28 from the slot 10 of the barrel and thus unlock it so that it can be turned by means of the key. The patron then locks the drawer by turning the key a half revolution anti-clockwise thereby to bring the arm 8 above the barrel, as shown in Fig. 15. During this turning movement of the barrel the gear 29 moves the rack 30 to the right, and when the rack has been moved into the position shown in Fig. 14, the head 32 will be moved out from under the rest 34 thereby allowing the member 19 to swing further downwardly until the end 23 thereof is brought against the magnet 37. When in this position the coin is released and passes down the chute 39 into a suitable box or compartment adapted to receive the coins. The magnet 37 holds the member 19 in this depressed position and thus holds the projection 28 raised out of the slot 10

in the barrel so as to permit the barrel to freely rotate into the position shown in Fig. 15. When in this position the bolt 3 is fully projected and the drawer is locked and the parts are then in the position shown in Figs. 1 and 3.

When the member 19 is in the position shown in Fig. 15, the projection 28 is withdrawn from the notch 27 of the key so that the key is free to be withdrawn from the lock. The turning of the barrel through 180° from the position shown in Fig. 12 to that shown in Fig. 15 has moved the rack 30 to its extreme position to the right and the head 32 has been brought under the end 23, and in doing this it has swung the pivoted arm 35 to one side. This completes the operation of depositing the article in the drawer and the locking of the drawer by the patron.

The next procedure is for the proprietor to unlock the drawer with his master key, remove the article, cleanse the article, and then replace the article and lock the drawer again. The operation of the lock during this stage is illustrated in Figs. 16 to 19, inclusive, and the master key which the proprietor uses is illustrated in Fig. 9. This key is indicated at 40 and it is made with the portion 41 to enter the slot of the barrel, but is not provided with the extension 13. It also has the inclined surface 42, but does not have the notches 27. In place of that it has the portions 43. When the master key is inserted the parts are in the position shown in Fig. 15 with the coin-receiving end 23 of the member 19 held in its depressed position by the magnet and with the projection 28 raised. The proprietor inserts the key into the barrel and then turns the key clockwise thereby to withdraw the bolt 3. This turning movement of the key is freely permitted because of the position in which the member 19 is held. During the first part of the turning movement of the key the rack 30 is withdrawn into the position shown in Fig. 16 and during the latter or final turning movement of the key, said rack is thrown into the position shown in Fig. 17, in which the drawer is fully unlocked. As the rack 30 moves from the position shown in Fig. 16 to that shown in Fig. 17, the cam 33 thereof engages the extension 34 and raises the member 19 slightly thereby disconnecting it from the magnet 37. The proprietor then removes the article and locks the drawer again. The locking of the drawer by the turning of the key through 180° anti-clockwise brings the parts into the position shown in Fig. 18 with the rack 30 moved to its extreme position to the right. During this movement of the rack the member 19 is not controlled by the magnet 37 because it has been separated therefrom sufficiently so that the weighted end 22 of said member 19 over-

comes the attraction of the magnet. After the bolt has been fully projected, then the master key 40 is withdrawn, and when this occurs, the weighted end 22 of the member 19 swings said member into the position shown in Fig. 19.

When the proprietor returns with the cleansed article to replace said article in the drawer, then the operations shown in Figs. 16 to 19 are repeated. The patron now returns with his key and will insert the key into the lock, as shown in Fig. 20. During the inserting of the key the inclined portion 44 of the key will engage the projection 28 and produce a slight swinging movement in the arm 19, but as soon as the key has been fully inserted, the weighted end 22 of the member 19 will restore it to the position shown in Fig. 20, and when in this position the key-locking projection 28 will occupy the portion 26 of the slot 10 and prevent the barrel from being turned. In order to permit the patron to turn the key and unlock the drawer he is obliged to deposit another coin 25 in the coin slot 24, as shown in Fig. 21. The depositing of the coin partially depresses the coin-actuating member 19 and brings the arm 35 against the head 32. This arm stops the movement of the member 19 before the end 23 has been brought into engagement with the magnet 37 and also before said end has moved downwardly to a point to permit the coin to pass the corner 38 of the coin slot. This movement of the member 19, however, is sufficient to elevate the projection 28 above the barrel so that the patron can then turn the key and barrel in a clockwise direction thereby withdrawing the bolt. As soon as the turning movement of the key commences the rack 30 is moved to the left and withdrawn from the arm 35, thus allowing the member 19 to complete its downward movement under the weight of the coin into engagement with the magnet 37, the latter operating to hold the member 19 in this position. This final movement of the member 19 releases the coin 25 so that it passes down the chute 39 into a suitable receptacle. When the drawer is fully unlocked the rack 30 has been moved to its extreme position to the left, thereby bringing the cam 33 against the extension 34 and raising the arm 19 away from the magnet 37, thus breaking the electric attraction. The parts are thus restored to the position shown in Fig. 12 and the patron can then remove his cleansed article and depart.

When the parts have been restored to the position shown in Fig. 12, the projection 28 on the member 19 again enters the slot 10 of the barrel 7 thereby locking the barrel from turning movement and, therefore, when the patron leaves the drawer it will be unlocked but the lock will be locked from operation until another coin is again deposited in the coin chute.

It will be seen that I have provided a simple mechanism which involves the deposit of one coin to lock the drawer by the patron and another coin to unlock the drawer.

5 While in the above description of the invention I have referred to its use in connection with a cabinet or depository for receiving articles to be laundered or cleansed and for returning said articles when cleansed 10 to the owner, yet it will be obvious that the invention is not limited to this use, but may be used in various ways where it is desired to provide for the insertion of a coin in order to lock a compartment or container and the insertion of another coin in order to unlock the compartment or container. The particular character of the articles which are to be placed in the drawer, container, or compartment is, 15 of course, immaterial so far as the invention is concerned.

I claim:

1. In a lock for a drawer or other container, the combination with a key-operated bolt, of a coin slot, coin-controlled means 25 normally preventing the bolt from being operated to lock the drawer but adapted to permit such operation upon the deposit of a coin in the coin slot, and means to maintain said coin-controlled means inoperative so far 30 as preventing the bolt from being operated is concerned while said bolt is actuated to unlock the drawer and then to lock it again, said coin-controlled means again becoming operative after the second locking of the 35 drawer to lock the bolt from movement.

2. In a lock for a drawer or other container, the combination with a key-operated bolt, of a key to operate said bolt, a coin slot, and coin-controlled means normally 40 preventing the bolt from being operated to lock the drawer but adapted to permit such operation upon the deposit of a coin in the coin slot, said means being rendered operative by the subsequent unlocking and 45 locking of the drawer again to prevent the unlocking of the drawer when the key is inserted into the lock again but adapted to permit such operation upon the deposit of another coin.

3. In a lock for a drawer or other container, the combination with a barrel having a key slot, of a bolt connected thereto and operated by the rotation of the barrel, a coin slot, coin-controlled means normally locking the barrel from rotation while the drawer is 55 unlocked but constructed to permit such rotation upon the deposit of a coin in the coin slot, and means to maintain said coin-controlled means inoperative while the barrel is turned to unlock the drawer and then to 60 lock it again, said coin-controlled means then becoming operative again to lock the barrel from turning.

4. In a lock for a drawer or other container, the combination with a barrel having

a key slot, of a bolt connected thereto and operated by the rotation of the barrel, a key to rotate the barrel, a coin slot, and coin-controlled means normally locking the barrel from rotation while the drawer is unlocked but constructed to permit such rotation upon the deposit of a coin in the coin slot, said means rendered operative by the subsequent locking and unlocking of the drawer to prevent the rotation of the barrel 70 to withdraw the bolt when the key is again inserted into the barrel but adapted to permit such rotation upon the deposit of another coin. 75

5. In a lock for a drawer or other container, the combination with a rotatable barrel having a key slot, of a bolt connected to said barrel, a coin slot, a movable coin-actuated member normally locking the barrel from rotation when the drawer is unlocked, 80 said member being constructed to be actuated by a coin deposited in the coin slot to release the barrel, means to maintain said member inoperative while the barrel is turned to unlock the drawer and then to 90 lock it again, said member then becoming operative to lock the barrel from rotation. 95

6. In a lock for drawers and other containers, the combination with a rotatable barrel having a key slot, of a bolt connected to said barrel, a key to rotate the barrel, a coin slot, a movable coin-actuated member normally locking the barrel from rotative movement when the drawer is unlocked, said member being moved by a coin deposited in 100 the coin slot thereby to unlock the barrel, means to hold said member in its inoperative position after the drawer is locked and the key has been withdrawn, and means actuated by the unlocking and subsequent locking 105 of the drawer again by a master key to restore said coin-actuated member to normal position.

7. In a lock for drawers and other containers, the combination with a rotatable barrel having a key slot, of a bolt connected to the barrel, a coin slot, a movable coin-actuated member normally locking the barrel from rotation but arranged to release the barrel upon the insertion of a coin in the coin slot, a magnet to hold said member in its inoperative position in which it has been placed by said coin, and means actuated by the unlocking and subsequent locking of the drawer again by a master key to restore said member to operative position, in which it locks the barrel from turning movement whereby the insertion of another coin is necessary to permit the drawer to be unlocked again. 110 115 120 125

8. In a lock for a drawer or other container, the combination with a rotatable barrel having a key slot, of a bolt connected to said barrel, a coin slot, coin-controlled means normally preventing the rotation of the bar- 130

rel while the drawer is unlocked but arranged to release the barrel upon the insertion of a coin in the coin slot thereby permitting the drawer to be locked, said 5 means being rendered operative by a master key to lock the barrel from rotation after the drawer is locked whereby the insertion of a second coin is necessary to unlock the drawer.

9: In a lock for a drawer or other container the combination with a key-operated bolt, of a key, a coin slot, and coin-controlled means normally preventing the withdrawal of the key from the lock and the bolt from being operated when the drawer is unlocked 10 but adapted to release both the key and the bolt upon the insertion of a coin in the coin slot, said means again becoming operative to lock the bolt after the bolt has been unlocked and locked again by a master key.

10. In a lock for a drawer or other container, the combination with a key-operated bolt, of a key, a coin slot, and coin-controlled means normally preventing the withdrawal of the key from the lock and the bolt from 15 being operated when the drawer is unlocked but adapted to release both the key and the bolt upon the insertion of a coin in the coin

slot, said means being rendered operative by a master key to lock the bolt from movement after the drawer is locked, but adapted 20 to again release the bolt upon the insertion of a second coin.

11. In a lock for a drawer or other container, the combination with a key-operated bolt, of a coin slot, and coin-controlled means 25 normally preventing the bolt from being operated to lock the drawer but adapted to permit such operation upon the deposit of a coin in the coin slot, said means again becoming operative to lock the bolt from 30 movement after the bolt has been actuated to unlock and lock the drawer again.

12. In a lock for drawers or other containers, the combination with a key-operated bolt, of a coin slot, and means whereby the 35 bolt may be operated first to lock the drawer and then to unlock it by the insertion of two coins successively in the slot, said means permitting the bolt to be operated to 40 unlock and then lock the drawer between the 45 insertion of said coins.

In testimony whereof, I have signed my name to this specification.

MYER COHEN.
